C. A. ALDEN.

PROCESS OF MAKING RAILROAD FROGS AND PRODUCT THEREOF

FILED MAY 25, 1920

UNITED STATES PATENT OFFICE.

CHARLES AMES ALDEN, OF STEELTON, PENNSYLVANIA.

PROCESS OF MAKING RAILROAD FROGS AND PRODUCT THEREOF.

Application filed May 25, 1920. Serial No. 384,238.

To all whom it may concern:

Be it known that I, CHARLES AMES ALDEN, a citizen of the United States, and resident of Steelton, in the county of Dauphin and State of Pennsylvania, have invented certain new and useful Improvements in Processes of Making Railroad Frogs and Products Thereof, of which the following is a specification.

10 The present invention relates to a method of making railroad frogs and more particularly to the production of such frogs from a solid bar of rolled, pressed or forged metal. The invention is claimed broadly 15 in application 384,237.

The principal objects of the invention are to increase production and at the same time lower the costs of manufacture. Further objects consist in the provision of a frog 20 which has a minimum number of parts and is inherently strong and capable of standing up under all degrees of service.

To this end the method of this invention consists in operating on a solid bar of metal 25 of substantially uniform cross section to alter the shape at a point adjacent where the wings are to end to provide for the flaring of the wings and increased width of the flange-ways at this point, and forming the flange-ways in the top of the bar to provide the wings and point. If desired, the bar may be heat treated after the first operation.

Other objects and features of novelty will 35 be apparent from the description taken in connection with the drawings, in which Figure 1 is a plan elevation of a bar or blank from which the frog is constructed; Figure 2 is a cross sectional elevation of 40 the bar;

Figure 3 is a plan view of the bar after the first operation has been performed on the same;

Figure 4 is a sectional elevation taken 45 substantially on the line 4—4 of Figure 3;

Figure 5 is a sectional elevation taken substantially on the line 5—5 of Figure 3;

Figure 6 is a sectional elevation taken 50 substantially on the line 6—6 of Figure 3;

Figure 7 is a top plan view of the completed frog;

Figure 8 is a sectional elevation taken substantially on the line 8—8 of Figure 7;

Figure 9 is a sectional elevation taken 55 substantially on the line 9—9 of Figure 7;

Figure 10 is a sectional elevation taken substantially on the line 10—10 of Figure 7;

Figure 11 is a sectional elevation taken substantially on the line 11—11 of Figure 7;

Figure 12 is a sectional elevation taken 60 substantially on the line 12—12 of Figure 7; and

Figure 13 is a sectional elevation taken substantially on the line 13—13 of Figure 7.

According to the present invention the 65 frog is constructed from a solid rolled, pressed or forged blank or bar of substantially uniform cross section. Such a bar or blank may be termed a "worked" bar to distinguish from a casting.

Referring to the drawings Figures 1 and 2 illustrate a solid bar 440 of uniform cross section from which the frog is constructed, this bar having base flanges 442. The first operation consists in indenting the recess or 70 groove 441 in the bottom of the blank, this groove having different widths as indicated in the plan view, Figure 3, and sectional views, Figures 4, 5 and 6. The blank is not widened except at the region where the 75 wings are to end, as indicated by the section of Figure 6, at which section the central part of the groove may be made deeper; thus further widening the bar at this point. It will be observed that the cross sectional area 80 of the bar has not been changed by the formation of the recess. After these operations, which slightly elongate the bar, the same may be subjected to a suitable heat treatment to raise the elastic limit and ultimate strength. Thereafter the top of the 85 bar is formed with flange-ways 446 and 447, thus providing the wings 448 and 449 and the point 460. These flange-ways may be formed by removing the metal as by machining.

At one end the track rails are secured to the frog by the integral separator block 456, the removable bent splice plates 452, 453 and bolts 58. At the other end the track

rails are secured to the frog by the integral 100 separator block 457, the straight removable splice plates 454, 455 and bolts 58. As shown in Figures 8 and 13, the integral separator blocks 456 and 457 are properly shaped to

fit against the webs of the rails between the 105 base flanges and heads thereof. The sides of

the bar adjacent the base of the separator blocks or extensions are channeled or recessed to receive the splice plates. Thus at

one end the sides are formed with recesses 110

2
 470 and 471 for the splice plates 452 and 453, and at the other end the sides are formed with recesses 472 and 473 for the splice plates 454 and 455. The base flanges 442 at 5 the first mentioned end of the bar are cut away or removed for a length substantially the same as said recesses 470 and 471 and are narrowed at the other end. Further at the 10 first mentioned end the top of the bar is formed with the lateral cut away parts 474 and 475 so that the shoulders thus formed constitute smooth extensions of the outside surfaces of the heads of the track rails.

Preferably the frog is constructed from a 15 worked steel bar although the invention is not limited to this metal.

Although a specific illustration of the method has been described in detail, it is to be understood that the invention is not thus limited but includes modifications and changes which come within the scope of the appended claims.

Having thus described the invention what is claimed as new and desired to be secured 25 by Letters Patent is:

1. The process of making railroad frogs consisting in operating on a solid metal bar of substantially uniform cross sectional shape to form a recess in the bottom thereof 30 and to widen the bar at the region where the wings are to end, and removing metal from the top of the bar to form the flange-ways, wings and point.

2. The process of making railroad frogs 35 consisting in operating on a solid metal bar of substantially uniform cross sectional shape to form a recess in the bottom thereof and to widen the bar at the region where the wings are to end, and machining out metal 40 from the top of the bar to form the flange-ways, wings and point.

3. The process of making railroad frogs 45 consisting in operating on a solid metal bar of substantially uniform cross sectional shape to form a recess in the bottom thereof without altering the width of the bar except at the region where the wings are to end, the recess being deeper at this region thereby widening the bar, and forming 50 flange-ways in the top of the bar to provide the wings and point.

4. The process of making railroad frogs 55 consisting in operating on a solid metal bar of substantially uniform cross sectional shape to form a recess in the bottom thereof without altering the width of the bar except at the region where the wings are to end, the recess being deeper at this region thereby widening the bar, machining out 60 the flange-ways in the top of the bar to provide the wings and point and forming narrowed centrally disposed extensions at the ends of the bar to the lateral sides of which the track rails are adapted to be secured.

5. The process of making railroad frogs

consisting in operating on a solid metal bar of substantially uniform cross sectional shape to form a recess in the bottom thereof and to widen the bar at the region where the wings are to end, heat treating the bar 70 and removing metal from the top of the bar to form the flange-ways, wings and point.

6. The process of making railroad frogs 75 consisting in operating on a solid bar of substantially uniform cross sectional shape to widen the same at the region where the wings are to end, removing stock from the top of the bar to form the flange-ways, wings and point, and operating on an end 80 of the bar to form an integral separator block, adapted to have the track rails secured to the outside lateral sides thereof.

7. The process of making railroad frogs 85 consisting in pressing in a portion of the bottom of a solid bar of substantially uniform cross sectional shape to widen the same at the region where the wings are to end, removing stock from the top of the bar to form the flange-ways, wings and point, and 90 operating on an end of the bar to form an integral separator block adapted to have the track rails secured to the outside lateral sides thereof.

8. The process of making railroad frogs 95 consisting in indenting one of the horizontal surfaces of a solid bar of substantially uniform cross sectional shape to widen the same at the region where the wings are to end, removing stock from the top of the 100 bar to form the flange-ways, wing and point, and operating on an end of the bar to form an integral separator block adapted to have the track rails secured to the outside lateral sides thereof.

9. The process of making railroad frogs 105 consisting in indenting the bottom of a solid metal bar of substantially uniform cross sectional shape thereby forming a recess and widening the bar at the region where the 110 wings are to end, and removing metal from the top of the bar to form the flange-ways, wings and point.

10. The process of making a one piece railroad frog having an integral separator 115 block at each end adapted to have the track rails secured to the outer sides thereof, consisting in operating on a solid bar of substantially uniform cross sectional shape to indent a recess in the bottom thereof the 120 length of which is less than the distance between the adjacent ends of said blocks, said operation widening the bar only at the region where the wings are to end, forming flange-ways in the top of the bar to provide 125 the wings and point, and operating on the end portions of the bar to form said blocks.

11. The process of making a one piece railroad frog having an integral separator 130

block at each end adapted to have the track rails secured to the outer sides thereof, consisting in operating on a solid bar having base flanges, said bar being of substantially 5 uniform cross sectional shape, to indent a recess in the bottom thereof the length of which is less than the distance between the adjacent ends of said blocks, said operation widening the bar only at the region where 10 the wings are to end, forming flange-ways in the top of the bar to provide the wings and point, and operating on the end portions of the bar to form said blocks, and recesses in the sides of the bar adjacent said 15 blocks for the splice plates and removing the base flanges to a point inside the inner ends of said recesses.

12. The process of making railroad frogs consisting in operating on a solid worked 20 metal bar of substantially uniform cross sectional shape to form the tips of the wings, and machining out the flangeways to complete the wings and form the point.

13. As an article of manufacture, a non- 25 cast single piece railroad frog having flangeways, wings, a point and means at the ends thereof for securing the rails thereto, said frog being formed from a solid bar of worked metal of uniform cross sectional shape.

30 14. As an article of manufacture, a non- cast single piece railroad frog having flangeways, wings, a point and means at the ends thereof for securing the rails thereto, said frog being formed from a solid bar of worked 35 metal of uniform cross sectional shape.

15. A blank adapted to be made into a single piece railroad frog comprising a solid bar of worked metal of uniform cross sec-

tional shape, said shape being a rectangle with flanges projecting from a pair of adjacent corners of said rectangle. 40

16. The process of making a one piece railroad frog having an integral separator block at one end adapted to have the track rails secured to the outer sides thereof, consisting in operating on a bar of substantially uniform cross section to widen the same at the region where the wings are to end, forming the flangeways, wings and point, and operating on an end of the bar to form an integral separator block and recesses in the sides of the bar adjacent said block for the splice plates. 45 50

17. As an article of manufacture a rolled steel frog of substantially uniform cross sectional area throughout the greater part of its length having an integral separator block at each end adapted to have the track rails secured to the outer sides thereof, each block being of gradually increasing width from 55 its neck to its end, said frog being formed with recesses in the sides thereof adjoining said blocks for the splice plates. 60

18. As an article of manufacture a rolled steel frog of substantially uniform cross sectional area throughout the greater part of its length having an integral separator block at each end adapted to have the track rails secured to the outer sides thereof, each block being of gradually increasing width from 65 its neck to its end and having its sides adapted to snugly fit into the channel in the sides of the rails. 70

In testimony whereof I affix my signature.

CHARLES AMES ALDEN.
